UNITED STATES PATENT OFFICE.

JOHN M. PENDLETON, OF NEW YORK, N. Y., ASSIGNOR TO THE EQUITABLE ELECTRIC COMPANY, OF SAME PLACE.

ELECTRIC MOTOR.

SPECIFICATION forming part of Letters Patent No. 321,049, dated June 30, 1885.

Application filed October 7, 1884. (No model.)

To all whom it may concern:

Be it known that I, JOHN M. PENDLETON, a citizen of the United States, and a resident of New York, county and State of New York, 5 have invented certain new and useful Improvements in Electromotors, of which the following is a specification.

The object of this invention is the construction of a simple and cheap electromotor of 10 high efficiency having no dead-centers.

The invention consists of a field-magnet with pole-pieces diametrically arranged and cores of one continuous piece of iron, and an armature fitted to rotate in suitable bearings between the magnet-poles, and composed of three equidistant radial cores, each provided with a bobbin of insulated wire, the inner and outer ends of each adjacent pair of which are connected to separate plates of a three-part commutator secured to the shaft of the armature. Two contact-brushes diametrically arranged 15 convey the electric current to the commutator, so that when one of them is changing the flow of current from one plate to the succeeding one 20 the other brush bears on the central part of the third plate. By this arrangement two poles of the armature having similar polarity are always on one side of a central line passing through the field-magnet poles, and the third 25 pole of opposite polarity on the other side of the central line, except during the short interval of time when either of the armature-poles is directly on said central line, in which position the armature-cores change their polarity. Then there is one armature-pole on each 30 side of the central line oppositely polarized, and of the right sense for mutual attraction with the field-magnet poles they are approaching, according to the direction of rotation of the 35 armature, from which it will be seen that the motor will start in all positions of its armature, and all the magnetic effects due to the current employed are fully utilized.

The invention further relates to improvements in the contact-brush holders, which, with the other novel features of the machine, will be fully described by reference had to the accompanying drawings, in which—

Figure 1 is a front elevation of my improved 40 motor, partly in section. Fig. 2 is a plan view.

Fig. 3 is a section on the line xx . Fig. 4 is a diagram view of the field-magnet poles and armature, and Fig. 5 is an enlarged view of one of the brush-holders.

The field-magnet system comprises a single 55 piece of iron, of which a and b are the poles; c and c' , the cores; and d , the flange-base projecting from the outer side of the lower pole, b . The coils or bobbins e and e' of insulated 60 wire are placed on the cores c and c' , which are curved, as shown, so that the whole of the field closely surrounds the armature, which rotates in the interior between the poles a and b , thereby making the machine very compact, and obtaining a maximum effect from the 65 mass of iron and the amount of wire contained in the coils e and e' of the field-magnet system.

The armature consists of one piece of iron having three radial arms, $f f' f''$, provided with polar extensions, and in the central hub of which is secured the shaft g , fitted to rotate in bearings $h h'$, forming part of light frames of diamagnetic material secured to the front and rear sides of the magnet-poles a and b . Upon the radial arms $f f' f''$ are placed the coils of insulated wire $i i' i''$, which are connected to a commutator secured to the shaft g , and having three separate plates, $j j' j''$. These connections are made by means of a ring, k , of insulating material placed over one end of the commutator, and having three screws, which force the ends of the coils $i i' i''$, passed in pairs through holes in the ring, in close contact with the plate of the commutator, as follows: the inner end of i and the outer end of i' with 75 plate j , the inner end of i' and the outer end of i'' with plate j' , and the inner end of i'' and the outer end of i with plate j'' .

Two contact-brushes, $l l'$, bear on opposite sides of the commutator. They are fastened 80 to the posts m and m' , so as to be readily attached thereto and adjusted by means of slotted yokes n and n' , provided with screw-threaded stems and thumb-nuts, and fitted in longitudinal slots in the posts m and m' , the said brushes 85 being passed through the slots in the yokes n and n' and clamped firmly against one side of the posts m and m' by the thumb-nuts which bear against the other sides of the posts.

With the connections of the field-magnet 90

coils and the armature as shown the current enters the free end of the coil *e* (marked +) passes through said coil to the brush *l*, thence through the armature, and, by the brush *l'*, passes to the coil *e'*, and leaves the machine by the free ends of this coil (marked -.)

It will be observed that when the armature is in the position shown in Fig. 5 the upper magnet-pole, *a*, having a south polarity, and 10 the lower one, *b*, a north polarity, the current entering the armature through commutator-plate *j* imparts to the polar extensions of the cores *f'* and *f''* a north polarity, and to that of the core *f'* a south polarity, which are correct 15 for mutual action with the poles *a* and *b* to cause the armature to rotate, as indicated by the arrow, and that when the core *f'* is on the central line, *x*, the brush *l* changes from plate *j* to plate *j'*, at which time the brush *l'* is on 20 the center of plate *j''* and the poles *f'* and *f''* the only active ones, so that the core is of south polarity in its movement from the south pole *a* to the north pole *b*. Similar actions take 25 place relatively between all the poles of the armature and the magnet-poles as said armature rotates.

The question of lead necessary to give the contact-brushes is not here considered, it being well understood by those conversant in the art. 30 Having now described the construction and operation of my invention, what I claim, and desire to secure by Letters Patent, is—

1. In an electromotor, the combination of an armature having three radial cores, each provided with a coil of wire, with a commutator having three plates, each connected to an inner and outer end of the coils on adjacent cores, and two brushes diametrically arranged in contact with the commutator, substantially as and for the purpose set forth. 35

2. The combination, with a field-magnet having two poles diametrically arranged, and their cores of one continuous piece of metal, of a three-pole armature and commutator, and brushes constructed and connected, as described, whereby the two poles of the armature on one side of a central line passing through the field-poles are of one polarity of opposite kind to the third pole on the other side of the central line, substantially as set forth. 40

3. In combination, the brush *l*, slotted yoke *n*, provided with a threaded stem and thumb-nut, and the slotted post *m*, substantially as set forth. 45

In testimony whereof I have hereunto set 50 my hand at New York, county and State of New York, this 4th day of October, 1884.

JOHN M. PENDLETON.
